UNITED STATES PATENT OFFICE.

F. ROBERT SEIDENSTICKER, OF MERIDEN, CONNECTICUT, ASSIGNOR TO THE
BRADLEY & HUBBARD MANUFACTURING COMPANY, OF SAME PLACE.

DESIGN FOR A LAMP-FOUNT.

SPECIFICATION forming part of Design No. 12,282, dated May 24, 1881.

Application filed April 16, 1881. Term of patent 3½ years.

To all whom it may concern:

Be it known that I, F. ROBT. SEIDENSTICKER, of Meriden, in the county of New Haven and State of Connecticut, have invented a new 5 Design for Lamp-Fount; and I do hereby declare the following, when taken in connection with the accompanying drawing and the letters of reference marked thereon, to be a full, clear, and exact description of the same, and 10 which said drawing constitutes part of this specification, and represents a front view.

This invention relates to a design for lamp-founts such as are used with metal bases, or for chandeliers or brackets; and it consists in 15 the configuration of the fount, as shown in the accompanying illustration.

From the bottom the fount expands, curving upward for a short distance, then curved inward and outward, forming an annular cavity, 20 *a*, the side of the fount above forming a series

of annular beads, *b*, and from the upper bead inclined upward and inward to the collar-opening *c*.

The surface of the fount may be ornamented by cutting, which ornamentation forms no part 25 of this design, the essential feature being the outline or configuration of the fount.

I claim—

The design for lamp-fount, in outline starting from the base, curved upward, thence inward and outward, forming an annular cavity, 30 *a*, a series of annular beads, *b*, on the side of the fount above, thence inclined upward and inward to the collar, all as shown in the accompanying illustration.

F. ROBERT SEIDENSTICKER.
